(57) **CLAIM**

The ornamental design for a dental cassette, as shown and described.

DESCRIPTION

FIG. 1 is a perspective view of a dental cassette showing our new design;

FIG. 2 is another perspective view thereof, in a closed configuration;

FIG. 3 is a top view thereof;

FIG. 4 is a bottom view thereof;

FIG. 5 is a side view thereof, the opposite side being a mirror image thereof;

FIG. 6 is an end view thereof; and,

FIG. 7 is an opposite end view thereof.
